UNITED STATES PATENT OFFICE.

ROBERT J. SIMS, OF SPOKANE, WASHINGTON.

FORM-LIFTING MECHANISM.

Application filed December 30, 1925, Serial No. 78,344. Renewed August 11, 1926.

My present invention relates to improvements in form lifting mechanism adapted especially for use as an attachment in connection with printing machines or presses.

5 As is well known to those skilled in the art of printing the form used in many instances is so excessively heavy as to require the services of several men for lifting the form and placing it on the press or its bed. The 10 space available for use by the men is limited and the danger of dropping the form and pieing the type is always present.

The primary object of my invention is the provision of means which may be operated 15 and controlled by one man for lifting and placing the form in position on its bed without danger of accident when proper care is observed in manipulating the lifting mechanism.

20 To this end the invention consists in a lift mechanism which when not in use may be stowed or stored out of the way and is readily accessible when required for use. The invention embodies an attachment supported 25 from the press frame and includes a carrier for the form, means for lifting the carrier and means for supporting or guiding the form as it is being lifted, together with certain novel combinations and arrangements 30 of parts as will hereinafter be more fully set forth and claimed.

In the accompanying drawings I have illustrated one complete example of the physical embodiment of my invention where- 35 in the parts are combined and arranged according to the best mode I have thus far devised for the practical application of the principles of my invention.

Figure 1 is a view in elevation showing 40 the lifting mechanism applied to a printing machine frame, in position for use with a printing form shown in dotted lines ready to be lifted.

Figure 2 is a view in side elevation of the 45 mechanism of Figure 1, illustrating by dotted lines the lifting movement of the form.

Figure 3 is an enlarged transverse sectional view of the carrier and its connections, at line 3-3 Figure 1.

50 Figure 4 is a detail view at one end of the operating part of the lifting mechanism, indicating by dotted lines the mechanism stowed or stored out of the way when not in use.

55 In order that the general arrangement and

relation of parts may readily be understood I have indicated by the numeral 1 the frame of a well known type of printing machine or press and a conventional representation as 2 of the form.

60 The lifting mechanism is used as an attachment which may be applied to printing presses now in use or be associated as an accessory of the press during the manufacture of the printing press or printing ma- 65 chine.

In carrying out my invention I utilize a carrier which extends transversely of the press and is adapted to be supported on the floor at one end of the press for the recep- 70 tion of the form 2 preparatory to lifting the form into place. The carrier is in the form of a straight metallic bar or body 3, which is provided near its respective ends with supporting feet or blocks 4, 4 which not only 75 perform the function of supporting the carrier on the floor, but also add weight to the carrier in order that a stable support may be provided for the form as it is being lifted.

In its upper face the carrier is fashioned 80 with a longitudinally extending groove 5, open at both ends and forming a pair of parallel retaining ribs or flanges 6, 6, between which the form is supported in the groove. The form may be slid into the groove from 85 one end of the carrier and positioned (indicated in Figures 1 and 2) between the guide flanges 6, 6, and as the carrier is lifted or elevated the form is supported and guided to position where it can readily be placed 90 on the bed of the press, as indicated by dotted lines in Figure 2.

95 For lifting the carrier I provide a hoist mechanism supported from the press-frame 1 by means of a pair of hangers or brackets 7 and 8 which are bolted at the underside of the feed table or other suitable portion of the printing press. A winding roll 9 and its shaft 10 are journaled in bearing slots 11 of the hangers 7 and 8, and a ratchet wheel 12 on the shaft and pawl 13 pivoted on one of the hangers are used to control rotation of the shaft and its roll 9. A hand wheel 14 and knob 15 are affixed at one end of the shaft for rotating the roll and its shaft in 105 the bearing slots 11.

A duplex hoisting cable is affixed as at 16 to the longitudinal center of the winding roll and its ends 17 and 18 diverge downwardly therefrom and are passed through eyes or 110

apertures 19 that extend transversely through the body of carrier 3, preferably at the enlarged portions or feet 4 of the carrier. The upper walls of these apertures or holes are rounded as indicated in Figure 3 to reduce friction and consequent wear on the cable and to afford facile movement of the carrier as it is lifted.

When the carrier is supported on the floor 10 the ends of the two branches of the single cable pass upwardly from the inner side of the carrier and their extremities have anchoring straps or bands 20, fashioned preferably of metal and secured thereto as at 21. 15 These annular bands or straps encircle the spaced grooved portions 22 of a supporting and guide roller 23 which is provided with a shaft 24 that is journaled in open bearing slots 25 of bearing brackets 26 bolted to 20 the press frame 1.

As the winding roll or drum 9 is turned by means of the hand wheel it will be apparent that the winding action of the cable will lift the carrier from the floor as the two 25 branches of the cable slip through the apertures 19 of the carrier. The weight of the form and that of the carrier is sufficient to stabilize the movement of the carrier as it is being lifted, and the form, which rests near 30 its upper end against the roller 23, is lifted, and guided by its sliding contact with the roller 23 to position where it may readily be transferred to the bed of the press.

When not required for use the mechanism 35 may be stowed or stored away by bodily lifting the roller 23 and its shaft 24 from the bearing slots 25 of the brackets 26. The ends of the shaft may then be placed in auxiliary slots 27 (Fig. 4) of the hangers 7 and 8, as 40 indicated by dotted lines in Fig. 4. After the roller is thus stored away the hand wheel 14 may be turned to wind the cable and elevate the carrier to position between and under the two rolls or rollers 9 and 23, where

the mechanism is readily accessible for further use when needed. 45

Having thus fully described my invention, what I claim as new and desire to secure by Letters Patent is—

1. The combination with a printing press 50 frame of a winding roll and manually operated means therefor, of a hoist cable and anchoring means for its ends, and a form-carrier suspended with a slipping engagement on said cable. 55

2. The combination with a support of a lifting mechanism comprising a hoist roll and a cable secured thereto, and anchoring means for the diverging ends of said cable, and a carrier suspended on the diverging 60 portions of the cable and adapted to slide with relation to the cable.

3. In a form lifting mechanism the combination with a carrier having spaced apertures therein, of a duplex-cable having a slip 65 engagement with the apertured carrier, a stationary guide roller, and means for anchoring the ends of the duplex cable on said guide roller.

4. In a form lifting mechanism the combination with a carrier having a form-supporting groove in its upper face and spaced, transverse openings therein, of a hoisting roll and a cable secured thereto, said cable having duplicate portions passing through 75 said openings, a guide roller, and means on said guide roller for anchoring the cable-ends. 80

5. The combination with a hoisting roll and a guide roller having spaced annular 85 grooves, of a duplex cable having end straps anchored in said grooves and secured to said hoisting roll, and a carrier having apertures therein for slipping engagement with said cable. 85

In testimony whereof I affix my signature,

ROBERT J. SIMS.
